UNITED STATES PATENT OFFICE

EMANUEL J. PERRY, OF NEW BEDFORD, MASSACHUSETTS, ASSIGNOR TO THE AMERICAN LAUNDRY MACHINERY COMPANY, OF NORWOOD, OHIO, A CORPORATION OF OHIO

WASHING MACHINE

Application filed July 1, 1926. Serial No. 119,944.

The invention relates to improvements in power driven washing machines of the type now generally used in steam laundries and the like.

It is an object of the invention to provide an improved form of controlling mechanism for controlling the power applied to the washing cylinder of a washing machine.

It is a further object of the invention to provide an improved mechanism for lifting the washing cylinder to and from the casing of the machine.

The invention more particularly relates to a washing machine having improved control means for controlling the source of power to the machine whereby the washing cylinder will, upon the disconnection of the power thereto, be arrested in its movement in a centered position and locked in such position whereby the garments will readily dump by gravity when the cylinder is lifted from the casing.

The control mechanism forming a part of this invention, while particularly applicable for use in connection with washing machines, is also useful in connection with other machines where a cylinder is rotated in a casing, and also where it may be desirable to lift the cylinder from the casing.

The invention more particularly relates to control mechanism for a washing machine of the general type disclosed in detail in my co-pending application, Serial No. 50,076, filed August 13, 1925.

In the accompanying drawings,

Fig. 1 illustrates an end elevation of the machine.

Fig. 2 illustrates the front elevation.

Fig. 3 illustrates the rear elevation.

Fig. 4 illustrates the elevation of the opposite end of the machine.

Fig. 5 is an enlarged sectional view of the raising and lowering control mechanism.

Fig. 6 is a sectional view taken on line 6-6 of Fig. 5.

Fig. 7 is a sectional view on line 7-7 of Fig. 5.

Fig. 8 is an enlarged longitudinal sectional view of the driving mechanism.

Fig. 9 is a transverse sectional view thereof on line 9 of Fig. 8.

Fig. 10 is an enlarged section of the cylinder driving connection.

Fig. 11 is an enlarged elevation of the rotation control mechanism.

Fig. 12 is a plan view thereof.

Fig. 13 is a transverse section thereof.

Fig. 14 is a similar view.

Fig. 15 is a detail view of the spring pulley structure.

Fig. 16 is a detail view of the brake mechanism.

Fig. 17 is a detail cross sectional view of the cylinder and casing and illustrates the mounting for the casing closure.

Referring now more particularly to the drawings, wherein like reference characters indicate corresponding parts, the numeral 1 designates a washing casing having the usual supporting legs, etc. In this casing there is disposed a rotating washing cylinder 2. This cylinder is preferably perforated. The casing has a slidable closure or door 3, while the cylinder likewise has a hinged sliding door by means of which the contents thereof may be discharged. It will be understood, of course, that the closure or door 3 is slidable in suitable guide channels formed in the framework of the hinged casing section 77, this section being in turn hinged to the main casing 1 as indicated at 77' in Figures 1, 3, and 4 of the drawings. The hinged sliding door forming a part of the rotary washing cylinder is of a construction common to this type of machine but is shown in detail in Fig. 17.

The washing cylinder is provided with a pair of stub axles 4 journalled in suitable bearings formed in the lifting segments 5, one segment being disposed at each side of the machine. Each segment is pivoted on a bearing 6 at one end thereof to the casing of the machine, while the peripheral portion of each segment is provided with gear teeth 7. Each segment, as before stated, is provided with bearings receiving bearing extensions projecting from the rotating cylinder 2.

In machines of this character, it is customary to alternately rotate the cylinder in

opposite directions for the purpose of washing the clothes contained therein. To rotate this cylinder, a motor 8 is provided which is connected with a current in such a manner that its armature shaft 9 alternately rotates in one direction and then the other. This armature shaft includes a loose splice or connection 9a for permitting a limited sliding movement and carries thereon a keyed gear 10. The gear 10 is disposed within the housing 11. In this housing there is also a gear 12 keyed to the shaft 13 which extends longitudinally of the machine at the rear thereof and carries at its outer ends gears 14 around which the sprocket chains 15 travel, said chains also engaging the teeth of gears 16 on a shaft 17 extending across the machine, which shaft in turn carries gears 18 penetrating recesses or slots in the back of the machine casing and meshing with the teeth of the gears 21 which are mounted at each end of the washing cylinder. These gears 21 are endless, and the rotation of the armature shaft therefore rotates the cylinder within the casing. By this mechanism, the washing cylinder is rotated, its rotation in opposite directions being secured by reason of the electrical connection with the motor in a manner which is well known in the art.

To utilize the motor 8, to raise the washing cylinder from the casing to the position shown in Fig. 1, a shaft 22 is connected with the end of the armature shaft, the connection being of a character to cause the armature shaft to be moved longitudinally but permitting the shaft to rotate relative to the shaft 22. It will be observed that a hand lever 23 is pivoted at one side of the machine and that this lever is connected by a link 24 with the shaft 22. Mounted on the frame of the machine is a casting 25 having a cam-way slot 26 therein into which a pin 27 on the shaft 22 projects. Obviously, upon a shifting of the lever, this cam slot and pin causes the shaft 22 to be moved longitudinally, in turn moving the armature shaft and the gear 10 thereon. The movement of this lever therefore shifts gear 10 out of mesh with the gear 12 and into mesh with the gear 28. This gear 28 carries a sleeve 29 to which there is fitted a bevel gear 30 in turn meshing with a beveled gear 31 on the shaft 32, driving a worm 33, and meshing with a gear 34 on a shaft 35. The shaft 35 at each end carries a gear 36 which meshes with a reduction gear 37, which reduction gear in turn meshes with the peripheral teeth 7 of the segments 5. Obviously, when the lever 23 is moved, say, to a forward position, the gears are meshed as herein described, and when current is permitted to pass to the motor, the washing cylinder will be lifted from the casing. The passage of the current to the motor is controlled by a depending element 38, movable with the shaft 22, which is connected by a slot connec-

tion with a switch 39, this switch, when moved to its right-hand position in Fig. 2, serving to close the circuit to permit the current to pass to the motor. It only reaches this position when the lever 23 has been operated to engage the gears 10 and 28 or, in other words, to throw the proper gears into mesh to lift the washing cylinder from the machine.

The gears 10, 12 and 28 are suitably housed as by means of a casing 11 embracing said gears and the shafts 9 and 13 with which they are associated as clearly illustrated in Figures 8 and 9. It is also apparent from these figures that casing 11 has a laterally offset downward extension 11' which embraces shaft 35 and houses gears 33 and 34. Referring to Figs. 3 and 9, it will be apparent that this lower portion 11' of housing 11 extends downwardly at the rear of the machine and is supported by the center casing supporting standard. An automatic circuit controlling mechanism is housed in a suitable casing 44' disposed at the rear of the machine and suitably supported in position to be actuated by shaft 35 through gears 42 and 43.

It will be furthermore appreciated that a pair of control buttons 40 and 41 are provided, the button 40 being pressed to close the circuit to rotate the motor 8 in a direction to lift the washing cylinder from the casing, while an operation of the button 41 reverses the rotation of the motor to lower the washing cylinder into the casing, it being appreciated that in each of these circuits, a switch 39 is provided, so that either circuit cannot be completed until the gears are properly meshed.

It will be appreciated that the washing cylinder rises to the position shown in dotted lines Fig. 1, and that it also must be lowered into the casing. Mechanism is therefore provided for stopping this cylinder when it reaches its open position and also when it reaches its closed position. With this in mind, the shaft 35 carries a gear 42 which meshes with a gear 43 on a threaded shaft 44 as shown in Figs. 5 and 6. This shaft 44 carries a nut 45 which is maintained against a rotary movement by rods 46 passing through apertures in the nut. The rods 46 are disposed on either side of the threaded shaft 44 and in parallel relation therewith and have their ends mounted in the end walls of the switch control casing. The nut carries forward and rear switch braking lugs 47. It will be appreciated that at one end of the shaft 44 a switch mechanism 48 is provided. At the other end, a switch mechanism 49 is provided. As soon as the push button 40 has been operated to raise the cylinder from the machine, and just as soon as the traveling nut 45 reaches the switch 48, it shifts the movable switch arm, breaking this circuit. This brings the motor to a halt, and at a time when the washing cylinder occupies a raised

position. When the switch button 41 is operated, however, the current then passes to the motor through a second circuit so that the motor is operated, and the nut 44 travels rearwardly until it is lug engages the movable arm of the switch 49. This causes an operation of this switch, breaking the circuit which occurs at a time when the washing cylinder is lowered in the casing.

10 The present invention has particular reference to a control mechanism for stopping the rotation of the washing cylinder, and for centering and locking this cylinder in its desired position. If the contents of the washing cylinder have been sufficiently treated, and it is desired to remove them from the washing machine, the lever 50 is grasped and moved from the full line position A to the dotted line position B in Fig. 11. This lever 15 is loosely mounted on a shaft 51, carried by the housing or casing of the machine. The lever travels through a cam slot 52 in the housing 53 so that a movement toward the operator shifts the lever laterally to the right, 20 (Fig. 13). The lever has a connection with a dog 54 so that this dog shifts with the lever but is permitted to oscillate independently of the lever. This connection between the lever 50 and the dog 54 may be of any suitable type. As an example, the lever may be provided with an annular radially projecting flange spaced axially a sufficient distance to fit in an annular internal groove formed in the dog. This connection will cause the dog 25 to move axially with the lever and will permit the dog and lever to have relative annular movement. The dog 54 is connected by a link 55 with a disc 56 keyed to the shaft 4 of the washing cylinder so that it constantly reciprocates during the rotation of this cylinder. This dog furthermore carries a 30 lug 57 rigidly fitted to the one side face thereof. A second dog 58 is also loosely mounted on the shaft 51. This dog also carries a locking plate 59. The dog 58 is connected by a lever 60 with the rod 61 by a coupling 62. This rod 61 connects at its opposite end through a coupling 63 with an arm 65 secured to a rock shaft 66 which is journaled in brackets secured to the motor support. An arm 66' is secured to shaft 66 at a point intermediate the ends of the latter and is adapted to coact with the switch arm 64' protruding from switch box 64. The end of shaft 55 66 opposite arm 65 has fixed thereto an arm 66'' connected through suitable linkage to the contracting brake band 67 fitting around the drum 68 on the armature shaft of the motor. This brake is normally maintained by the 60 spring 69 in an inoperative position, but when the rod 61 is shifted, the band is tightly drawn around the surface of the drum 68. When the lever 50 is moved to the dotted line position B, the locking faces 57 and 59 of 65 the dogs 54 and 58 are brought into align-

ing paths so that a movement of the dog 54, imparted thereto by the link 55, oscillates the dog 58. This causes an operation of the connecting rod 61 which in turn rocks shaft 66, thereby breaking the motor circuit 70 through switch 64 and bringing the motor shaft and associated mechanism to a stop by means of brake 67. At this time, the washing cylinder has come to a halt where the opening 69' in the disk 56 is in alignment 75 with the locking bolt 70 as shown in Fig. 2. The parts are so arranged that the washing cylinder will cease its movement so that this lock opening 69' is in alignment with the locking bolt 70. This is because of the positioning of the parts, the length of the rod 61 which has a turnbuckle 60' therein by means of which its length can be adjusted so that the washing cylinder will always stop at the position shown in Fig. 11 when the power is disconnected by the mechanism thus described. This disconnects the source of power to the motor through this driving circuit. The operating lever 50 is then moved to the position shown by the reference character C, (Fig. 11). In doing this, the bolt 70 is forced into the bolt opening 69' in the disc 56 keyed to the washing cylinder. This locks the washing cylinder in its centered position. It furthermore releases dog 58 95 from dog 54, thereby permitting spring 58' to return the dog 58 to its normal position and release the brake 67 operating on the drum 68. When the parts are in this positions, it is apparent that all motion of the 100 washing cylinder has ceased, and that this cylinder is centered and locked in a proper position so that when it is raised outward the casing 1, the discharge opening therein will be directed toward the floor of the 105 laundry.

To raise the cylinder from the machine, the operating lever 23 is then pushed forward. This shifts the shaft 22 through the pin and cam-way connection 26 and 27 so 110 that the gears 10 and 28 are brought into mesh. At this time, the switch plug 39 is operated, so that current may pass to the motor 8 through a circuit including switch 40 to rotate the armature shaft in a given direction. As the shaft 22 is shifted, and at the time the gear 10 is thrown into mesh with the gear 28, the switch 39 is likewise shifted so that the circuit is now complete, and the armature shaft starts to rotate. This causes 115 a lifting of the cylinder from the casing as the upper hinged section 77 thereof opens and permits the cylinder to rise to the position shown in Fig. 1. At this time the lever 50 occupies a position corresponding to the 120 dotted line position C in Fig. 11. During this raising movement, the nut 45 is traveling on the threaded shaft, and when this nut coacts with its switch lever, it serves to break the circuit, this occurring at the time the 125

washing cylinder reaches its downward position. As a precaution, in the event this mechanism should not work, the segments 5 carry stops 78 which coact with portions of the casings enclosing the gears 37 should the washing cylinder be moved outwardly to a position beyond that at which the switch operating mechanism is set to come into play. At this time, the contents of the washing cylinder are discharged by gravity into waiting receptacles. To lower the cylinder in the casing, the switch 41 is operated, closing a second circuit to the motor 8, causing this motor to rotate in an opposite direction, and to lower the washing cylinder in the machine by the gearing heretofore described. The traveling nut 44 is shifted, during this movement, in a reverse direction, and when the washing cylinder is disposed within the casing, this nut breaks the electric circuit by operating the switch lever disposed in its path, stopping the operation of the motor. The hand lever 23 is then thrown to its neutral position, and the various closures of the apparatus moved to a closed position, it being assumed, of course, that a new supply of clothes has been deposited in the rotating cylinder. The machine is then ready for a second operation. The motor operating current can be introduced to the motor at this time when the lever 50 is in its neutral position, the lever 23 in its neutral position, and one of the switch buttons 40—41 operated, permitting the current to pass through the circuit and to the motor 8, whereupon the cylinder will rotate, first in one direction and then in the other, and will continue to so rotate until the control lever 50 is again operated.

40 It will be appreciated that by the control mechanism herein described, embodying the lever 50 and its associated parts, the movement of the cylinder can be arrested at any time and the cylinder will be locked in a centered position. By merely shifting the lever, the dogs 54 and 58 are brought into operative relation, and the movement of the cylinder is imparted to the dog 58 by the dog 54 to slightly rotate this dog and shift the lever 60. This immediately breaks the circuit to the motor. The link 55 and the rod 61 are so connected and are of such length that when the circuit is broken, the washing cylinder will be halted in its movement in a determined or proper centered position. When in this position, the lock receiving opening 69' is in alignment with the bolt 70. When the switch 64 is operated to break the circuit to the motor, the forward movement of the hand lever 50 causes the cylinder to be locked in this centered position, and the brake, which had been previously applied on the movement of this lever toward the operator, is released.

65 The term "centered" as herein used is in-

tended to designate a predetermined rotative position of the cylinder. It will be appreciated, of course, that it is desirable to stop the cylinder with its opening in substantial registration with the casing opening and that this is true regardless of whether the cylinder is to be removed from the casing. However, this feature is of particular importance in connection with a self-dumping machine since the discharge opening of the cylinder must be properly disposed in order to permit automatic discharge when the cylinder is in dumping position. It is this desired predetermined rotative position of the cylinder to which the term "centered" is herein applied.

Having thus described the invention, what I claim is:

1. In a washing machine, the combination with a casing, of a rotating washing cylinder therein, means for supporting the cylinder for movement into and from the casing, power operated driving means for rotating the cylinder, means for connecting and disconnecting the driven mechanism with respect to its source of power, means for centering and locking the cylinder in a centered position and for releasing the cylinder to permit movement from said centered position, connections leading from said last two mentioned means to a common control device, and manually operable means connected to said common control device for first disconnecting said driving mechanism from its source of power to stop the rotation of the cylinder and to thereafter center and lock the cylinder.

2. In a washing machine, the combination with a casing, of a rotatable cylinder therein, a switch controlled source of power, driving mechanism between said power and the cylinder for rotating the cylinder in the casing, a control lever, a dog shiftable by said lever, a driving connection between the dog and said cylinder for reciprocating said dog, a second dog, a connection between said second dog and the switch for the source of power, and means for connecting said dogs upon the shifting of the first dog toward the second by the actuation of said control lever, whereby the switch is actuated by the rotation of the driven cylinder.

3. In a washing machine, the combination with a casing, of a cylinder disposed therein, power means for lifting the cylinder from the casing, comprising a motor, driving connections between the motor and the cylinder, a control lever for said connections, and means driven by said driving connections for automatically stopping the motor drive when the cylinder reaches the limit of either its outward or inward position with reference to the casing.

4. In a washing machine, the combination with a casing, of a cylinder disposed

therein, power means for lifting the cylinder from the casing, comprising a motor, driving connections between the motor and the cylinder, a control lever for said connections, means driven by said driving connections for automatically stopping the motor drive when the cylinder reaches the limit of either its outward or inward position, said means comprising a traveling element operable by the driving means for raising said cylinder, and a switch adjacent the limit of movement of said element in either direction.

5. In a washing machine, the combination with a casing, of a washing cylinder therein, a source of power, driving mechanism between said source of power and said cylinder for rotating the cylinder, a control for the source of power, comprising a control lever, 15 a pair of connectable and disconnectable parts, one connected with the cylinder to be actuated thereby and the other connected with the source of power for controlling the same, and a connection between said lever 20 and one of said parts for moving said parts into connected relation whereby one is driven by the other.

6. In a washing machine, the combination with a casing, of a washing cylinder therein, a source of power, driving mechanism between said source of power and said cylinder for rotating the cylinder, a control for the source of power, including a control lever, 30 a pair of connectable and disconnectable parts, one connected with the cylinder for movement therewith and the other with the source of power, a connection between said lever and one of said parts for moving said parts into connected relation whereby one 35 is driven by the other when the lever is moved in one direction, and means operated by a movement of the lever in another direction for locking the cylinder in a predetermined position.

45 7. In a control device for a machine of the character described, the combination with a lever, of a pair of loosely mounted selectively interlockable parts, means connecting one of said parts with a driven element for operating said part, means connecting the other part with a source of power for controlling the latter, and means connecting said control lever with said part connected with the driven element to move said parts into interlocking relation whereby the part connected with the driven element actuates the part connected with the source of power.

8. In a washing machine, the combination with a casing, of a washing cylinder rotatable therein, means for supporting the cylinder for pivotal movement into and from the casing, a power driven mechanism for rotating said cylinder, means for connecting and disconnecting the driven mechanism with respect to its source of power, means for cen-

tering and locking the cylinder in a centered position and for releasing the cylinder to permit movement from said centered position, and control means for said cylinder operable to successively actuate said last two mentioned means.

9. In a washing machine, the combination with a casing, of a washing cylinder rotatable therein, a power driven mechanism for rotating the cylinder, means for connecting and disconnecting the driven mechanism with respect to its source of power, means for centering and locking the cylinder in a centered position and for releasing the cylinder to permit movement from said centered position, and a single manually operable control device for actuating said last two mentioned means.

10. In a washing machine, the combination with a casing, of a washing cylinder therein, means pivotally supporting the cylinder for movement into and from the casing, a source of power, driving mechanism between said source of power and the cylinder for rotating the cylinder in the casing, means for disconnecting the cylinder from the source of power, means driven by the rotation of the cylinder for operating said last mentioned means when connected thereto, and manual means for connecting and disconnecting the means driven by the rotation of the cylinder with the said disconnecting means.

11. The combination with a washing machine having a casing, of a rotatable cylinder therefor, power driven mechanism for rotating the cylinder, means for disconnecting the power from said mechanism, braking means for the mechanism, a common operating device for both of said means, means driven by the rotation of the cylinder for actuating said common operating device when connected thereto and a lever for controlling the connection between the common operating device and its actuating means.

In testimony whereof I affix my signature.

EMANUEL J. PERRY.
